UNITED STATES PATENT OFFICE

OSCAR ANTON WIBERG, OF FINSPOONG, SWEDEN.

ELASTIC-FLUID TURBINE.

1,223,915.

Specification of Letters Patent. Patented Apr. 24, 1917.

Application filed January 15, 1917. Serial No. 142,526.

To all whom it may concern:

Be it known that I, OSCAR ANTON WIBERG, a subject of the King of Sweden, residing at Finspong, Sweden, have invented certain 5 new and useful Improvements in Elastic-Fluid Turbines, of which the following is a specification.

The present invention relates to radial flow elastic fluid turbines and specifically to 10 that type heretofore invented by me and covered by United States Patent No. 1,202,135, issued October 24, 1916. Briefly the turbine shown in said patent comprises a system of blades through which the motive fluid flows outward in a radial direction, and a second system of blades through 15 which the motive fluid flows axially, generally in two multiple paths to the exhaust outlet, there being a deflector which directs the motive fluid in its passage. The radial flow system comprises sets of blades and carrying members therefor that rotate in opposite directions, and the axial flow system comprises sets of stationary fluid directing 20 means and sets of blades which rotate in opposite directions, the latter being carried by the same members which carry the blades of the radial flow system.

As shown in the patent, the diameter of 25 the outer blades of the radial flow system is substantially the same as that of the inner ends of the stationary directing means or guide blades of the axial flow system. I have found that with the parts arranged as described, the motive fluid which possesses 30 considerable residual velocity on leaving the radial flow system, has a tendency, due to this residual velocity, to flow directly outward to the deflector and shunt those portions of the stationary and moving blades 35 of the axial flow system nearest the radial flow system. As a result of this the effective action of the blades is decreased with a corresponding loss in economy.

40 I have discovered that if the motive fluid leaving the radial flow system is caused to give up its residual velocity wholly, or in large part, the objectionable shunting of the inner ends of the axial flow system will be avoided and the efficiency of the turbine substantially improved.

In carrying out my invention I provide 45 an annular chamber between the two systems of such size and character that it acts as a diffuser in which the residual velocity of the motive fluid is converted into pressure.

As a result of this the motive fluid, instead of rushing past the inner ends of the axial flow system to the deflector, will flow smoothly and uniformly through the spaces 50 between the stationary directing blades or devices, and thence act effectively on the co-operating rotating blades.

In the accompanying drawing is shown one of the embodiments of my invention, 65 said drawing being a partial axial section of a turbine.

a designates a part of the turbine casing which incloses the working parts and is connected as usual to a suitable exhaust conduit, not shown. In the casing are rotors *b* and *c* arranged to revolve in opposite directions, the shafts for which are omitted from the drawing. Mounted on the rotors are concentric rings of blades *d* and *e* through 70 which the motive fluid flows outward in a generally radial direction. The blades are divided into relatively short lengths between which are strengthening rings *o* of suitable material. The rotors are provided 75 with enlarged rims *l* in which the blades *f* and *g* of the axial flow system are suitably mounted. The rims are connected to the main body of the disks by portions *m* which gradually decrease in thickness toward the 80 rims to give the proper radial stresses 85 therein.

The stationary blades are mounted at their outer ends in a ring *k* which is generally V-shaped in cross-section. Its side 90 walls are curved to form a deflector so as to assist in directing the fluid from the radial to the axial system. The inner ends of the blades are secured in rings *n* which form the side walls of the diffuser chamber *p*. The 95 inner surface of each ring *n* is bored or turned slightly larger than the annular projection *q* on the rotors *b* and *c* so that when in operation there will only be a small clearance through which the motive fluid can escape. The outer diameters of the rings *n* are slightly greater than the root diameter of the rows of blades *f* and *g* and are suitably shaped to assist in directing the motive fluid. The opposite ends of the ring *k* may, 100 if desired, overhang the outer ends of the rotating blades *f* and *g* to form a cover therefor and prevent loss by leakages. To this end it is desirable to extend the outer ends of the rotating blades somewhat beyond the corresponding ends of the stationary blades, as shown.

The inner boundary or inlet of the diffuser chamber p is defined by the outer ring of blades e , and its sides by the rings n . The outlet of the chamber is defined by a cylinder whose diameter corresponds to that of said rings, although to a certain extent the spaces on opposite sides of the deflector may be considered as a part thereof. The outlet should be enough larger than the inlet to cause the residual velocity of the fluid leaving the blades to be gradually converted into pressure so that the motive fluid instead of shunting the inner portions of the blades of the axial flow system will flow smoothly and uniformly through the blades' spaces, thereby acting effectively on said blades throughout their length. I have found by actual experience if the distance between the outer blade rings e and the outer diameter of the rings n is equal to from three to five times the width of the outer blades that satisfactory results will be obtained.

Another advantage of my improved construction resides in the fact that, due to the enlargement of the rotor, the blades do not have to be so long as in the prior construction to afford the necessary space for the low pressure motive fluid. Further, the increased diameter of the rotor results in a higher relative speed of the blades of the axial system and hence the effective action thereof is improved.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. In an elastic fluid turbine, the combination of members which rotate in opposite direction and have concentric rows of blades through which the motive fluid flows radially outward, an axial flow system of larger diameter than the radial flow system which comprises stationary blades and blades that rotate with said members, and an annular diffuser chamber which surrounds the radial flow system, has a smaller inlet than outlet and is located between said

systems, the said chamber acting to reduce the residual velocity of the exhaust as it flows from one system to the other.

2. In an elastic fluid turbine, the combination of a radial flow blade system, a pair of members which carry the blades of said system and rotate in opposite directions, each of said members having an enlarged rim, an axial flow system comprising stationary fluid directing means and rotating blades carried by said rims, and an annular diffuser chamber which is situated between said enlarged rims, receives the motive fluid exhausting from the radial blade system and after decreasing its residual velocity delivers it to said stationary directing means and to the rotating blades on said rims.

3. In an elastic fluid turbine, the combination of a radial flow blade system, a pair of members which carry the blades of said system and rotate in opposite directions, each of said members having an enlarged rim, an axial flow blade system comprising rows of stationary and rotating blades which surround the radial flow system, rings to which the inner ends of the stationary blades are attached, said rings being located between said members, and an annular diffuser chamber located between the rings which enlarges from its inlet to its outlet by an amount sufficient to reduce the residual velocity of the motive fluid received from the radial system, said chamber delivering fluid in multiple to said rows of stationary blades.

4. In an elastic fluid turbine, the combination of axially extending blades arranged in concentric rows and through which the motive fluid flows from the axis outwardly, radially extending stationary and rotating blades which surround the axial blades and through which the motive fluid flows axially, the inner ends of the stationary radial blades being separated from the axial blades by a distance equal to at least three times the width of the outer row of axial blades to form a chamber, and means for directing the motive fluid into said stationary blades.

In testimony whereof I affix my signature in presence of two witnesses.

OSCAR ANTON WIBERG.
